UNITED STATES PATENT OFFICE

ROBERT M. PAGE, OF WASHINGTON, DISTRICT OF COLUMBIA

RELAXATION CIRCUIT OSCILLATOR

Application filed February 11, 1930. Serial No. 427,622.

My invention relates broadly to high frequency oscillation generators and more particularly to a relaxation oscillation circuit.

One of the objects of my invention is to provide a circuit arrangement for a relaxation oscillation system having means for controlling the ratio of charging time to discharge time in the condenser circuit associated with the oscillation system.

Another object of my invention is to provide a relaxation circuit oscillator with means for selecting and fixing the period of charging time of the condenser system associated with the oscillator with respect to the period of discharge time for securing oscillations of predetermined frequency which are highly stable in character.

A further object of my invention is to provide a circuit arrangement for a screen grid type of electron tube relaxation circuit oscillator having means in circuit with the electrode of the electron tube system for adjusting the ratio of charging time of the condenser circuit associated with the relaxation oscillator system with respect to discharging time thereof.

Still another object of my invention is to provide a relaxation circuit arrangement for a multiple grid electron tube system with means connected to selected grids for regulating the discharge time of the condenser system with respect to the charging time of the condenser system.

Other and further objects of my invention will be understood from the specification hereinafter following by reference to the accompanying drawings, in which:

Figure 1 diagrammatically shows the circuit arrangement of my invention applied to a screen grid relaxation oscillator; Fig. 2 shows a modified circuit arrangement for the relaxation oscillator of my invention; Fig. 3 shows a still further modified circuit for the relaxation oscillator of my invention; Fig. 4 shows another modification of the relaxation circuit oscillator of my invention; Figs. 5, 6 and 7 show modifications of the relaxation circuit of my invention employing multiple grid electron tubes; Fig. 8 is an ex-

planatory diagram showing the equivalent condenser circuit during the charging portion of the cycle; Fig. 9 is a reproduction of an oscillogram of the oscillator of my invention showing a condition especially favorable to frequency multiplication in the ratio of 42 to 1; and Fig. 10 shows the reproduction of an oscillogram of the circuit of my invention arranged to operate with a multiplication ratio of 2 to 1.

In my study of relaxation circuit oscillators for frequency division at high frequencies, I have found that in circuits heretofore known that the period of oscillation is unequally divided between the charging time and the discharging time of the condenser in the relaxation circuit, the charging time being much less than the discharge time. This unequal division of time period results in relatively poor operation of the relaxation circuit oscillator for certain purposes.

I have found that for the best results in frequency division at relatively high frequencies and for certain other purposes, considerable improvement results when the charging time of the condenser in the relaxation circuit is made equal to the discharge time, or where the charging time bears some definite and controllable relation to the discharging time. In order to control the ratio of charging time to discharging time, I provide a circuit arrangement for a relaxation circuit oscillator wherein a resistance is introduced in circuit with the condenser in the relaxation circuit, or in circuit with some one of the electrodes of a multiple electron tube used in the circuit, the resistance being fixed or variable and in such location and value in the circuit that the ratio of charging time to discharging time may be adjusted by selecting the value of the resistance. The entire output of the oscillator can be concentrated into any desired time division irrespective of the frequency of oscillations. The resistance member also tends to stabilize the operation of the relaxation circuit oscillator which is essential when the oscillator is used for frequency division and synchronization work. I employ the principles of my invention.

tion in multiple grid electron tube circuits as will be hereinafter pointed out in detail.

In the relaxation oscillator, the oscillations consist of aperiodic pulses of electromotive force occurring in cyclic order, and the output is not necessarily of sine wave form. The frequency of a relaxation oscillator may be controlled by a submultiple of another periodic electromotive force. In one form of relaxation oscillator, an electron tube with two grids is used with resistance and capacity only. Such an oscillator is described in the Van der Pol Patent 1,744,935, dated January 28, 1930. The fact that in the relaxation oscillator the output frequency while of considerable amplitude, can be controlled by a higher frequency of extremely small amplitude, has suggested its use for frequency division. Such frequency division is possible in ratios up to several hundred to one. Attempts to thus employ relaxation oscillators heretofore known, have however shown them to drift in discrete steps from one submultiple frequency of the input to another while in operation, remaining on one step for only a relatively short time. In the system of my invention these undesirable operating characteristics are avoided and stable operation in frequency division is obtained.

The fundamental frequency of the relaxation oscillator is equal to the output frequency, and the working range of frequency may extend from the lowest frequencies to 100 kilocycles, of even to 200 or 300 kilocycles. The relaxation oscillator can however be controlled by frequencies up to several thousand kilocycles by utilizing sub-multiples of these higher frequencies. The improvement resulting from the circuits which are here described are particularly marked at frequencies above 500 cycles, and up to 100 kilocycles or more.

In Figure 1, the electron tube employing the principles of my invention has been designated by reference character 1 including cathode 2, inner grid 3, outer or screen grid 4, and plate electrode 5. The relaxation circuit is shown completed through high potential source 6 which connects at the positive side with plate electrode 5 and at its negative side with one side of cathode 2. A connection 7 extends between the outer or screen grid 4 and resistance 8 to the negative side of the high potential source 6 and there is a connection between inner grid 3 through resistance 9 to tapped connection 10 at positive potential in high potential source 6. The external circuits of the relaxation circuit oscillator are completed through condenser 11 and resistance 12, which in Fig. 1, have been shown connected in series and connected between the inner grid 3 and the outer or screen grid 4. The cathode 2 is heated by any suitable source such as battery 14.

In Fig. 2, I have shown the relaxation circuit oscillator as including the several ele-

ments shown in Fig. 1 but the condenser circuit is rearranged so that the condenser 11 has one side 11a thereof connected directly to the inner grid 3 while the other side 11b thereof connects to the outer or screen grid 4 through the resistance 12 arranged in series between the outer or screen grid 4, and the resistance 8. The inner grid 3 connects through resistance 9 with a point of positive potential in battery source 6 as indicated by reference character 10 in a manner similar to the arrangement described in Fig. 1.

In Fig. 3 I have shown a modified arrangement of the relaxation oscillator circuit in which the circuit including condenser 11 is completed by a connection between the terminal 11a of the condenser and the inner grid 3, while the terminal 11b of the condenser connects through resistance 12 with the outer or screen grid 4.

In Fig. 4 I have illustrated an arrangement of relaxation circuit wherein the condenser 11 is shunted by the resistance 12 and the shunted circuit thus formed connected between the inner grid 3 and the outer or screen grid 4.

In Figs. 5, 6 and 7, I have shown various arrangements of the elements in the relaxation circuit oscillator system by which the ratio of charging time to discharging time in the relaxation oscillator can be controlled. A three grid tube is shown in Fig. 5 designated at 15 including cathode 16, plate electrode 17, and grid electrodes 18, 19 and 20, respectively. The external circuits for the oscillator include resistance 21 in circuit between inner grid electrode 18 and one side of cathode 16. Resistance 22 connects between outer grid electrode 20 and the negative side of the high potential source 23. The relaxation circuit is completed through condenser 24 and series connected resistance 25 connected between outer grid electrode 20 and grid electrode 19. Resistance 26 is disposed between intermediate grid electrode 19 and a point of positive polarity 27 in battery source 23. The plate electrode 17 is connected to a point of high positive polarity on potential source 23 as indicated.

In Fig. 6 I have shown a modified arrangement of the relaxation circuit of Fig. 5 wherein the resistance 25 is disposed directly in series with grid electrode 20 and in series with resistance 22, returning to the negative side of battery 23 through lead 29. The condenser 24 connects between one end of the resistance 25 adjacent the end of resistance 22 and the other side of the condenser connects to grid electrode 19. The grid electrode connects through resistance 26, with the positive potential point 27 of high potential source 23. The plate electrode 17 connects to a point of positive polarity on battery source 6 as indicated.

In Fig. 7, resistance 25 is directly connected in shunt with condenser 24 and the shunt cir-

cuit thus formed connected between grid electrode 19 and grid electrode 20. The remaining parts of the circuit are similar to those described with reference to Figs. 5 and 6.

5 The relaxation circuit oscillator of my invention may have the resistance 12 disposed as has been described in different relationships with respect to the condenser. The resistance may be variable for selecting that 10 value which enables the charging time to be controlled with respect to the discharge time. In this manner the output of the oscillator on any desired harmonic may be increased and relatively high efficiency obtained. The 15 influence of the resistance in the control circuit is that a relatively high degree of stability in the operation of the relaxation circuit oscillator is obtained.

20 The operation of the circuit of my invention may be described as follows, with reference to Fig. 1, assuming that resistor 12 is omitted:

25 The voltage on the condenser is equal to the difference between inner grid and outer grid voltages. The inner grid voltage is the impressed battery voltage less the resistance drop through 9. The outer grid voltage is merely the resistance drop through 8. Suppose the cathode to be deenergized. The condenser voltage will then assume a value equal to that of the portion of battery 6 connected between cathode and the inner grid connection 10. Now let the cathode be energized. The high inner grid current that follows will 30 reduce the positive potential at 3 to only a fraction of its initial value, causing the condenser to discharge. The discharge current through 8 causes a high negative potential at 4 which potential decreases as the discharge current decreases. As the potential at 35 4 approaches filament potential it reaches the value at which plate current begins to flow and inner grid current is decreased. The accompanying increase in positive potential at 40 3 causes the condenser to begin to charge, the charging current through 8 putting the potential at 4 at a positive value. By virtue of the positive potential thus placed on the outer grid, the inner grid current is further 45 reduced and therefore the potential at 3 is further increased so that the condenser is caused to charge at a higher rate. The resulting high charging current through 8 causes a very high positive potential at 4 50 which now decreases as the condenser becomes charged and the charging current decreases. As the outer grid potential approaches cathode potential now from the positive direction, it reaches the value at which 55 plate current is reduced and inner grid current increased. The resulting decrease in potential at 3 soon causes the condenser to discharge, the high discharge current through 8 causing a high negative potential at 4, and 60 55 the cycle is repeated. The tube works con-

tinuously on saturation current considering the sum of the currents in the leads to plate 5, through resistor 8 and through resistor 9, and the shifts in inner grid voltage from one extreme to the other may be considered to 70 take place instantaneously.

As shown in Fig. 8, the condenser is charged through the external and internal resistances of the outer grid in parallel. This external resistance being of the order of 75 100,000 to 200,000 ohms, is much greater than the internal resistances during the charging portion of the cycle, when the outer grid is positive. The condenser therefore becomes charged very quickly through the comparatively low internal resistance. During the discharge portion of the cycle, however, the internal resistance to the reverse current is of the order of megohms, and the condenser discharges more slowly through the external resistance. Consequently, the discharge period 80 of the condenser and resistances 8 and 9 in series, constitutes the major portion of the period of oscillations in the circuit. These oscillations are stable and satisfactory for 85 frequency division and the other purposes heretofore mentioned.

90 The oscillations obtained with the circuit of Fig. 1 but with series resistance 12 omitted are shown by the oscillogram of Fig. 9. The plate voltage is shown at *a*, the inner grid voltage at *b*, and the outer grid voltage at *c*. *P* and *P'* represent the critical voltages of the outer grid, at which the direction of condenser current is reversed. This oscillogram 95 represents a condition especially favorable to frequency multiplication in the ratio of 42 to 1. For facilitating the study of the operation or for other purposes, the charging period may be lengthened with respect to 100 the discharge period. In the circuit of Fig. 1, this is accomplished by inserting a resistance 12 of suitable value directly in series with condenser 11. The new wave form so produced is shown by the oscillogram of Fig. 10, wherein the reference characters correspond to those of Fig. 9. The insertion of this resistance is seen to speed up the discharge and slow up the charge, thus operating 105 to equalize the two parts of the cycle.

110 Fig. 10 represents a condition especially favorable to frequency multiplication in the ratio of 2 to 1. Conditions favorable to desired ratios of frequency multiplication may be obtained by suitable selection of the value 115 of series resistance 12.

120 While I have described my invention in certain preferred embodiments, I desire that it be understood that modifications may be made by those skilled in the art and that no 125 limitations are intended other than are imposed by the scope of the appended claims.

125 What I claim as new and desire to secure by Letters Patent of the United States is as follows:

1. In a relaxation circuit oscillator, an electron tube including a cathode, a plate and a multiplicity of grid electrodes, an input circuit connected between said cathode and one of said grids, an output circuit connected to said anode, said circuits including impedance elements substantially free of inductive characteristics, and a circuit disposed between two of said grid electrodes and including an impedance element substantially free of inductive characteristics and a condenser, said impedance element operating to adjust the charging period of said condenser with respect to the discharge period thereof. 70
- 10 2. In a relaxation oscillator, an electron tube including a cathode, a plate and a plurality of grid electrodes, means for maintaining one of said grid electrodes and said plate electrode at different values of positive potential, an input circuit connected between said cathode and one of said grids, an output circuit connected to said anode, said circuits including impedance elements substantially free of inductive characteristics, and a circuit including a condenser and a resistance disposed between two of said grid electrodes, said resistance operating to control the charging period of said condenser with respect to the discharging period thereof. 75
- 20 3. In a relaxation circuit oscillator, an electron tube including a cathode, a plate and a plurality of grid electrodes, means for maintaining said plate electrode and one of said grid electrodes at different values of positive potential, impedances disposed in the external circuits of said oscillator, said impedances being substantially free of inductive characteristics, and a circuit including a condenser and a resistance connected between the grid electrode which is maintained at positive potential and another of said grid electrodes, said resistance operating to control the charging period of said condenser with respect to the discharging period thereof. 80
- 30 4. A relaxation circuit oscillator comprising an electron tube including a cathode, a plurality of grid electrodes and a plate electrode, an input circuit connected between said cathode and one of said grids, an output circuit connected to said anode, said circuits being substantially free of inductive effects, a source of potential for impressing a positive bias on one of said grid electrodes and a larger positive bias on said plate electrode, and a circuit inter-connecting two of said grid electrodes and including a condenser and a resistance in series, said resistance operating to control the charging period of said condenser with respect to the discharging period thereof. 85
- 40 5. In a relaxation oscillator, an electron tube having cathode, inner grid, outer grid, and anode, a resistor connected between said outer grid and said cathode, a source of potential connected between said cathode and said inner grid, a second source of potential connected between said inner grid and said anode, and a condenser and a second resistor connected in series between said inner grid and said outer grid. 90
- 50 6. In a relaxation oscillator, an electron tube having cathode, inner grid, outer grid and anode, a pair of resistors connected in series between said outer grid and said cathode, a source of potential connected between said cathode and said inner grid, a second source of potential connected between said inner grid and said anode, and a condenser connected between said inner grid and the common connection connecting said two resistors in series. 95
- 60 7. In a relaxation oscillator, an electron tube having cathode, inner grid, outer grid, and anode, a resistor connected between said outer grid and said cathode, a source of potential connected between said cathode and said inner grid, a second source of potential connected between said inner grid and said anode, and a condenser and a second resistor connected in series between said inner grid and said outer grid, said second resistor being connected adjacent said outer grid. 100
- 70 8. In a relaxation oscillator, an electron tube having cathode, inner grid, outer grid, and anode, a resistor connected between said outer grid and said cathode, a source of potential connected between said cathode and said inner grid, a second source of potential connected between said inner grid and said anode, and a condenser and a second resistor connected in parallel between said inner grid and said outer grid. 105
- 80 9. In a relaxation oscillator, an electron tube having cathode, anode, and a plurality of grids, a resistor connected between said cathode and one of said grids, a source of potential connected between said anode and another of said grids, a second source of potential connected between said last mentioned grid and said cathode, and a condenser and a second register connected in series between said first mentioned grid and said last mentioned grid. 110
- 90 10. In a relaxation oscillator, an electron tube having cathode, anode, and a plurality of grids, a pair of resistors connected in series between one of said grids and said cathode, a source of potential connected between said anode and another of said grids, a second source of potential connected between said last mentioned grid and said cathode, and a condenser connected between said last mentioned grid and the common connection connecting said two resistors in series. 115
- 100 11. In a relaxation oscillator, an electron tube having cathode, anode, and a plurality of grids, a resistor connected between said cathode and one of said grids, a source of potential connected between said anode and another of said grids, a second source of potential connected between said last mentioned grid and said cathode, and a condenser connected between said last mentioned grid and the common connection connecting said two resistors in series. 120
- 110 12. In a relaxation oscillator, an electron tube having cathode, inner grid, outer grid, and anode, a resistor connected between said outer grid and said cathode, a source of potential connected between said cathode and said inner grid, a second source of potential connected between said inner grid and said anode, and a condenser connected between said inner grid and the common connection connecting said two resistors in series. 125
- 120 13. In a relaxation oscillator, an electron tube having cathode, inner grid, outer grid, and anode, a resistor connected between said outer grid and said cathode, a source of potential connected between said cathode and said inner grid, a second source of potential connected between said inner grid and said anode, and a condenser connected between said inner grid and the common connection connecting said two resistors in series. 130

tential connected between said anode and another of said grids, a second source of potential connected between said last mentioned grid and said cathode, and a condenser and a second resistor connected in parallel between said first mentioned grid and said last mentioned grid.
